DESIGN FOR A RADIO CABINET

Leland G. Stone, Fort Wayne, Ind., assignor to
The Magnavox Company, Fort Wayne, Ind., a
corporation of Delaware

Application December 14, 1944, Serial No. 116,898

Term of patent 7 years

(Cl. D56—4)

To all whom it may concern:

Be it known that I, Leland George Stone, a citizen of the United States, residing at Fort Wayne, in the county of Allen, State of Indiana, have invented a new, original, and ornamental Design for a Radio Cabinet, of which the following is a specification, reference being had to the accompanying drawing, forming a part thereof.

In the drawing the single figure in the drawing is a front perspective view of a radio cabinet showing my design.

I claim:

The ornamental design for a radio cabinet, substantially as shown.

LELAND GEORGE STONE.
